FLEXIBLE MAGNETIC DATA-STORAGE STRIP

Eugene H. Irasek, Los Angeles, Calif., assignor to The National Cash Register Company, Dayton, Ohio, a corporation of Maryland

Filed July 14, 1961, Ser. No. 65,916

Term of patent 14 years

(Cl. D59—1)

FIG. 1 is an elevational view of a flexible magnetic data-storage strip embodying my new design.

FIG. 2 is a partial view of the flexible magnetic data-storage strip of FIG. 1, showing in detail the design along the upper border thereof.

I claim:

The ornamental design for a flexible magnetic data-storage strip, substantially as shown.
